UNITED STATES PATENT OFFICE.

LOTT FREDERICK AND GEORGE HUGH DUGAN, OF NORTH SUMMIT, PENNSYLVANIA; SAID DUGAN ASSIGNOR TO SAID FREDERICK.

WRENCH.

SPECIFICATION forming part of Letters Patent No. 608,767, dated August 9, 1898.

Application filed October 30, 1897. Serial No. 656,886. (No model.)

To all whom it may concern:

Be it known that we, LOTT FREDERICK and GEORGE HUGH DUGAN, citizens of the United States, residing at North Summit, in the 5 county of Indiana and State of Pennsylvania, have invented certain new and useful Improvements in Wrenches; and we do hereby declare the following to be a full, clear, and exact description of the invention, such as 10 will enable others skilled in the art to which it appertains to make and use the same.

Our invention, as will be hereinafter fully described and claimed, and illustrated in the accompanying drawings, relates to certain 15 new and useful improvements in "monkey-wrenches," which, as is well known, comprise that variety of wrench the jaws of which are readily adjustable to receive the varying sizes of nuts upon which they are brought to bear. 20 The object of our invention is to provide a reliable-efficient construction which will readily enable the operator to instantly adjust the jaws without the necessity of following the guiding-threads upon the post, and, 25 further, to so simplify the elements forming our improved wrench that the same may be very cheaply manufactured.

In the accompanying drawings, Figure 1 is a perspective view of our improved wrench 30 provided with the necessary accessories for rendering the parts coöperative. Fig. 2 is a longitudinal central section of Fig. 1. Fig. 3 is a perspective detail of the movable jaw and sleeve provided therefor. Fig. 4 is a detailed central section of the jaw-controller. 35 Fig. 5, 6, and 7 are detailed views of the guiding-collar employed upon the end of the controller contiguous to the handle.

Briefly stated, our invention consists in 40 providing a threaded post for the movable jaw and a rotatable longitudinally-movable controller for coöperating with said jaws, thus enabling the movable jaw to be readily placed in an adjusted position without the 45 necessity of following the threads upon said post.

The several details of our invention will be for convenience designated by figures, the 50 same figure being employed throughout the several views.

In carrying out our invention we provide the threaded post or body 1, having integrally formed upon the outer end thereof the fixed jaw 2, while the opposite end is provided with the stem 3, designed to receive a 55 tubular handle 4 of the usual or any preferred construction, said handle being secured in position by means of the shoulders 5 and the locking-nut 6, engaging with the threaded stem 7, as clearly shown in Figs. 1 and 2. The 60 post 1 is preferably threaded throughout the greater part of its length, though the section 8 thereof nearest the fixed jaw 2 is preferably left plain and may be provided with a square, 65 oblong, or other form of outline, the oblong variety of outline being illustrated in Fig. 1.

The movable jaw 9 is provided with an aperture designed to snugly fit and move upon the section 8 and also upon that part of the post provided with the guiding-ribs 70 10. The movable edge has integrally or otherwise secured thereto the guiding-barrel or tubular flange 11, also provided with an aperture for receiving the post, upon which it moves with the jaw 9.

Designed to coöperate with the barrel 11 is the controller 12, which is provided with a bore of sufficient diameter to permit it to turn upon the post 1, the inner wall of said bore being provided at opposite points with a series of transversely-disposed ribs or guides 13, designed to coöperate with the guiding-ribs 10, formed upon the post 1. The series of ribs 13 are disposed, as above stated, upon opposite sides of the internal bore of the controller and are coextensive in length with the length of the guiding-ribs 10, carried by the post, and it will be apparent that said ribs will coöperate simultaneously with the upper and lower series of ribs 10 when the controller is in the proper position, and, further, that all of said ribs will be disconnected from each other when the said controller is properly rotated to bring the ribs 13 alongside of the flattened wall 14 of the post, thus permitting 90 the controller to then be freely moved longitudinally upon said post until the movable jaw is brought to the desired position, when by a quarter-rotation of said controller the ribs 13 will be brought into engagement with 95 100

the ribs 10, and thus lock the jaw securely in position for coöperating with the fixed jaw, and thus enable the nut to be turned.

In Figs. 5, 6, and 7 we have shown a closing or finishing collar 15, which is provided with the stop-pin 16, corresponding in function with the stop-pin 17 formed upon the barrel 11, both being designed to positively check the controller 12 when the adjustable stop-pin 18 has been brought into a position to register with one of the apertures 19 or 20 formed upon the opposite face of the barrel 11.

The operation of our improved wrench may be stated to be as follows: The controller 12 is rotated until the series of ribs 13 formed thereon are brought out of engagement with the serrations or controlling-ribs 10, when said controller may be freely moved longitudinally, and incidentally moving the movable jaw to the desired point upon the post 1, when a reverse rotation or partial rotation of the controller 12 will again bring the series of ribs 13 into engagement with the series of controlling-ribs 10, and thus positively lock the jaw in an adjusted position. When the controller has been moved to the right or left the requisite distance to enable the adjustable stop 18 to take into one of the apertures 19 or 20, the ribs 21 will contact with the stop-pins 16 and 17, thereby enabling said regulating-stop to positively enter one of said apertures and reliably hold the controller against casual rotation and displacement during the operation of using the wrench. If deemed desirable, the series of ribs 13 may have their ends beveled or sharpened to more reliably insure their free entrance into engagement with the series of controlling-ribs 10.

Believing the advantages, construction, and operation of our improved wrench have been made fully apparent from the foregoing specification, considered in connection with the accompanying drawings, we will dispense with further reference thereto.

Having thus fully described our invention, what we claim as new, and desire to secure by Letters Patent, is—

1. In a wrench, a post having a fixed jaw and partial screw-guides in the opposite edges in combination with a movable jaw having a rearwardly-extending sleeve provided with an external groove, and a controller-sleeve having partial threads fitting said guides and a thread on its inner end engaging said external groove and means to lock the parts in position, all arranged as set forth. 50

2. In a wrench, a post having a fixed jaw and mutilated screw-threads in combination with a movable jaw having a rearwardly-extending tubular flange provided with an external groove, and a controller-sleeve having partial threads fitting said screw-threads and having an interiorly-reduced end provided with a thread taking into said external groove, 65 and means to lock the parts in position, all arranged as set forth.

3. In a wrench, the combination with a post having a fixed jaw with mutilated screw-threads, of a movable jaw having a rearwardly-extended tubular flange provided with an external groove, and a controller having an interiorly-reduced end provided with a thread engaging said external groove, and means to lock the same consisting of a recess 75 in the tubular flange and a spring-actuated pin in the controller fitting the recess, all arranged as set forth.

4. In a wrench, the combination with a post having mutilated screw-threads and a fixed 80 jaw, of a movable jaw having a rearwardly-extended sleeve, a controller having partial screw-threads fitting said mutilated threads, and also having interiorly-reduced ends, a closing-collar fitting the rear reduced end, 85 said sleeve fitting the forward reduced end, and means to lock the sleeve, the controller and the closing-collar, all in position, as set forth.

In testimony whereof we affix our signatures in presence of two witnesses.

LOTT FREDERICK.
GEORGE HUGH DUGAN.
